TISSUE HOLDER

Raymond U. H. Tegner, Lodi, Wis., assignor to Amerock Corporation, Rockford, Ill.Original design application Jan. 10, 1972, Ser. No.
216,871. Divided and this application Apr. 30.
1973, Ser. No. 355,332

Term of patent 14 years

Int. Cl. D6—06

U.S. Cl. D6—97

FIG. 1 is a side view of a tissue holder incorporating my new design.

FIG. 2 is a front view of the tissue holder.

FIG. 3 is a fragmentary sectional view taken along the line 3—3 in FIG. 2.

FIG. 4 is a fragmentary sectional view taken along the line 4—4 in FIG. 2.

This application is a division of my co-pending application Ser. No. 216,871, filed Jan. 10, 1972.

I claim:

The ornamental design for a tissue holder, as shown.
